UNITED STATES PATENT OFFICE.

RICHARD W. SHOEMAKER AND LAWSSEN H. GIDDINGS, OF PASADENA,
CALIFORNIA.

WAVE-RECEIVER.

SPECIFICATION forming part of Letters Patent No. 761,258, dated May 31, 1904.

Application filed May 2, 1902. Serial No. 105,681. (No model.)

To all whom it may concern:

Be it known that we, RICHARD W. SHOEMAKER and LAWSSEN H. GIDDINGS, both citizens of the United States, residing at Pasadena, in the county of Los Angeles and State of California, have invented a new and useful Wave-Receiver, of which the following is a specification.

Our invention relates to an instrument for detecting and receiving electric waves employed in wireless telegraphy, and has for one object to produce an instrument for receiving such waves in which the susceptibility to the waves is continuous and not destroyed after receiving each wave.

Another object is to provide a receiver in which the susceptibility to waves may be as an inherent quality and self-acting and the instrument always in condition to be influenced by a wave.

Another object is to provide a receiver of the character described which may be adjusted to different degrees of susceptibility.

Another object is to provide a receiver which will be susceptible to waves of a definite character and not influenced by magnetic influences—such, for instance, as are generated by rotating the armature of a dynamo.

Another object is to provide a receiver which does not require more than ordinary care in handling and which is capable of sustaining jars, shocks, and other disturbances and still retain the utmost degree of susceptibility.

A further object is to attain the aforesaid objects by an exceedingly simple device which is self-contained, portable, has but few parts and no delicate or moving mechanism.

When under the influence of a wave, the receiver is in an excited condition, and when the wave subsides the normal condition prevails. Thus the receiver may have two distinctive conditions, and its tendency is to change from one condition to the other to partake of either condition according to the presence or absence of a wave.

The accompanying drawing illustrates the invention.

1 is a mixture composed of particles of non-

conducting material *a* and particles of conducting material *b*. The mixture is contained in a tube 2, composed of non-conducting material. Plugs 3, composed of a conducting material, confine the mixture under pressure. The plugs 3 may be adjustably held in binding-posts 4, as shown. The plugs 3 and mixture 1 form an unbroken continuous conductor, the mixture 1 being under such a pressure that the particles of which it is composed are held from becoming dislodged or shaken from their positions. The exact pressure is ascertained by adjusting the plugs until the wave-receiver responds to the coming as well as to the going of a wave. As near as we have ascertained in practice the pressure used, in some cases with plugs one-tenth of an inch in diameter, was less than an ounce.

5 is a metallic shield which may inclose the instrument and from which it may be insulated by insulators 6. The shield may act to prevent waves from being conducted to the instrument except through the regular channels. The non-conducting particles and the conducting particles are thoroughly mixed and an even pressure is maintained throughout the mixture. The mixture forms a continuous conductor through which an electric current may be passed and has what may be termed a "tendency" quality or characteristic which allows it to assume distinctive relative conditions. One condition of the mixture may be such that it forms a relatively low resistance to the flow of an electric current, while another condition of the mixture may be such that it forms a relatively high resistance to the flow of an electric current. The mixture is susceptible to electric waves, and the presence or absence of a wave causes one condition or another to prevail. The prevailing condition of the mixture when not under the influence of a wave may be termed, for convenience, its "normal" condition, while the condition prevailing when the mixture is under the influence of a wave may be termed its "excited" condition. When an oscillatory wave is conducted to a mixture, the mixture assumes its excited condition and remains so during the presence of the wave. When the

2
wave dies, the mixture naturally assumes its normal condition.

The device may be arranged and used as a receiver in wireless-telegraph systems in practically the same manner in which the coherer has been used. When the resistance of the mixture is low, the electric current may pass therethrough with full strength. When an electric wave comes, the resistance of the mixture is raised, and by regulating the electric current to the right degree the resistance of the mixture when high may stop the current and divert it into other conductors, which may contain translating devices. As soon as the wave dies the current may again flow through the mixture, or the current may be made strong enough to continually flow through the mixture, and a translating device (not shown) of definite resistance may be connected in series with this receiver, so that when the resistance of the mixture is high the current passing therethrough will not affect the translating device. Thus when the resistance of the mixture becomes normal the current flows at full strength and overcomes the resistance of the translating device and causes it to operate, or translating devices may be used having a low resistance and when connected in parallel with the wave-receiver will act in a manner the reverse of that which has been just described on account of the current being diverted by the wave-receiver into or through the translating device.

From the foregoing it will be seen that the receiver is entirely automatic and that the quality, characteristic, or tendency of the mixture to assume the different conditions does not depend upon magnetic influence or any mechanical auxiliary device for its operation. The operation of the receiver is not influenced by the presence of the electric current.

The susceptibility of the mixture to the waves, or, in other words, its adjustability, may be regulated by varying the pressure against the mixture. No definite statement can be made to indicate the exact amount of pressure, as the receiver is adjusted until it works automatically—i. e., increases in resistance upon the coming of a wave and decreases in resistance upon the going of a wave. As stated, we find that when the adjustment is correct for this automatic action the pressure is probably about an ounce. More or less pressure may, however, be required under other conditions, and considerable variation in the pressure may be made without destroying its susceptibility.

Waves of a definite character are required to influence the receiver, and the operators may regulate the pressure on the mixture to suit the waves being received.

By experiment we have found that the exact materials and proportions thereof, which may be used in the construction of the receiver,

may be varied to a large extent. We have found in practice that the proportion of conducting particles and non-conducting particles may preferably be equal. The non-conducting particles may be relatively fine—for instance, gaging one hundred mesh—while the conducting particles may be coarser. A preferable material for the non-conducting particles is powdered glass. A preferable material for the conducting particles is a powdered alloy. The alloy may preferably contain one-third tin and two-thirds silver. A good material for the tube 2 is glass. The plugs 3 may be of soft iron. The box 5 is not essential; but the use of it allows greater latitude in adjustability. If the box is employed, it may be connected to the earth, as shown, by the ground connection 7. The ground connection from the box is a usual practice, although our experiments have not shown any particular advantage resulting therefrom.

8 and 9 designate conductors affording channels for the waves and the electric current.

It is evident that many variations in the kind of material used, proportions of the material, construction, and arrangement of the same may be made without departing from the spirit of our invention.

What we claim, and desire to secure by Letters Patent of the United States, is—

1. A wave-receiver embracing a medium of conducting and non-conducting substances which is directly influenced by the coming and going of a wave, and means for varying the susceptibility of the medium.

2. A wave-receiver embracing a medium of conducting and non-conducting substances which is directly influenced by the coming and going of a wave and means for producing a regulated pressure on the medium.

3. An oscillatory-wave receiver comprising a conductor, a portion of said conductor being a mixture of particles of glass and particles of conducting material, said mixture being susceptible to oscillatory waves, the resistance of said mixture being normally low when uninfluenced by said waves and being relatively high when influenced by said waves.

4. An oscillatory-wave receiver comprising a conductor, a portion of said conductor being a mixture of non-conducting particles and particles of an alloy of silver and tin, said mixture being susceptible to oscillatory waves, the resistance of said mixture being normally low when uninfluenced by said waves and being relatively high when influenced by said waves.

5. An oscillatory-wave receiver comprising a conductor, a portion of said conductor being a mixture of non-conducting particles and conducting particles, the conducting particles being larger than the non-conducting particles, said mixture being susceptible to oscillatory waves, the resistance of said mixture being normally relatively low when uninfluenced

by said waves and being relatively high when influenced by said waves.

6. A wave-receiver comprising a tube of non-conducting material, iron plugs in the tube and spaced apart, and a mixture in the space between the plugs consisting of powdered glass and a powdered alloy of silver and tin.

7. A wave-receiver comprising a tube of non-conducting material, iron plugs in the tube and spaced apart, and a mixture in the space between the plugs consisting of pow-

dered glass and a powdered alloy of silver and tin, and a metallic shield inclosing all of said parts.

In testimony whereof we have signed our names to this specification, in the presence of two subscribing witnesses, at Los Angeles, California, this 26th day of April, 1902.
